ADJUSTABLE PIPE WRENCH

Charles H. Strang, Brooklyn, N. Y.

Application July 15, 1954, Serial No. 443,500

2 Claims. (Cl. 81—98)

This invention relates to pipe wrenches.

It is an object of the present invention to provide an adjustable pipe wrench which may be employed in areas of limited clearance and wherein the jaws may be adjusted relative to each other by a sleeve rotatably mounted on the handle.

It is another object of the present invention to provide an adjustable pipe wrench which includes novel means for mounting the stationary jaw member.

For other objects and a better understanding of the invention, reference may be had to the following detailed description taken in connection with the accompanying drawing, in which:

Figure 1 is an elevation of a preferred embodiment of the present invention;

Fig. 2 is a longitudinal sectional view thereof;

Fig. 3 is a transverse sectional view taken along the line 3—3 of Fig. 1; and

Fig. 4 is a transverse sectional view taken along the line 4—4 of Fig. 1.

Referring now more in detail to the drawing, 10 represents an elongated shank provided with teeth 11 adjacent the handle portion 12 thereof, the end of the shank 10 remote from handle 12 being integrally formed with an inclined extension 13 having a bore 14 therethrough, substantially as illustrated.

A stationary jaw 15 is integrally formed with a shank portion 16 which passes through the bore 14 and which is retained therein by means of a pin 17, the end of the shank 16 remote from jaw 15 being integrally formed with a laterally extending portion 18 adapted to abut the lower end of the extension 13.

A moving jaw 19 is integrally formed with a shank 20 having a longitudinal bore 21 therethrough and within which is slidably disposed the shank 10, the jaw 19 being adapted to cooperate with the jaw 15 to secure therebetween a pipe 21 (Fig. 2).

As a means of adjusting the jaw 19 relative to the jaw 15, an elongated sleeve 22 knurled on its outer surface to facilitate the rotation thereof is internally threaded and screwed onto the threaded portion 11 of shank 10 adjacent to the shank 20. The end of the shank 20 adjacent the sleeve 22 is provided with an annular groove 23 and an annular ridge 24, the annular groove 23 receiving therewithin rotatably a circular flange 25 provided on the end of the sleeve 22, the ridge 24 being rotatably received within an annular groove 26 provided in sleeve 22 adjacent the flange 25 whereby to rotatably connect the shank 20 with sleeve 22 and to insure the movement of the jaw 19 in the same direction as the sleeve 22.

It will be noted that, since the pin 17 holds the jaw 15 in place, the pipe 21 is first clamped between the jaws 15 and 19 by operating the sleeve 22, and is then rotated by swinging the handle 12 clockwise (as viewed in either Fig. 1 or Fig. 2), such movement of the handle 12 bringing the lip 18 into position against the end of the extension 13 so that the latter elements relieve the pin 17 of most of the stress. The sleeve 22 is of elongated length whereby to provide greater strength. Thus, by rotating the sleeve 22, the jaws 15 and 19 may be brought together about the pipe 21 in an improved manner.

While various changes may be made in the detail construction, it shall be understood that such changes shall be within the function and scope of the present invention as defined by the appended claims.

2

What I claim as new and desire to protect by Letters Patent of the United States is:

1. A pipe wrench having an elongated shank having an externally threaded portion and a handle portion adjacent said externally threaded portion, a pipe-engaging jaw comprising a shank having a bore therethrough receiving said first shank slidably therethrough and a pipe-engaging jaw integrally formed at one end of said shank, a stationary jaw cooperable with said first jaw, means for mounting said stationary jaw at that end of said first shank remote from said handle portion, said first jaw extending laterally and being provided with an arcuate toothed portion, an elongated sleeve screw threaded onto said externally threaded portion of said first shank adjacent said first jaw shank, said sleeve being knurled on its outer surface, said first jaw shank having an internal annular groove near said sleeve and an annular internal ridge adjacent said annular groove, said sleeve at that end thereof adjacent said first jaw shank having an annular ridge adapted to be received within said annular groove, said sleeve adjacent said annular ridge having a second annular groove adapted to receive rotatably therewithin said first jaw shank annular ridge, said stationary jaw comprising a jaw portion having an arcuate toothed portion cooperable with said first jaw toothed portion whereby to secure a pipe therebetween, and a shank portion inclined from said stationary jaw, said means for mounting said stationary jaw comprising an integral inclined extension on said first shank at the end thereof remote from said handle portion, said inclined extension having a longitudinal bore therethrough for receiving said inclined stationary jaw shank portion therewithin, a pin piercing said extension and inclined shank portion, and a laterally extending flange on that end of said inclined shank portion remote from said stationary jaw, said flange being engageable by an outer end of said inclined extension upon application of torque to said handle portion of said first shank.

2. A pipe wrench comprising an elongated shank having an externally threaded portion and a handle portion adjacent said externally threaded portion, a pipe-engaging jaw slideable along said shank and externally threaded portion, said jaw extending laterally and being provided with an arcuate toothed portion means for adjusting said jaw along said shank, a stationary jaw cooperable with said first jaw and means for mounting said stationary jaw at that end of said shank remote from said handle portion, said stationary jaw comprising a jaw portion having an arcuate toothed portion cooperable with said first jaw toothed portion whereby to secure a pipe therebetween, and a shank portion inclined from said stationary jaw, said means for mounting said stationary jaw comprising an integral inclined extension on said first shank at the end thereof remote from said handle portion, said inclined extension having a longitudinal bore therethrough for receiving said stationary jaw inclined shank portion therewithin, a pin piercing said extension and inclined shank portion, and a laterally extending flange on that end of said inclined shank portion remote from said stationary jaw, said flange being engageable by an outer end of said inclined extension upon application of torque to said handle portion of said first shank.
